UNITED STATES PATENT OFFICE.

JOHN H. MACARTNEY AND JACK MACARTNEY, OF LOS ANGELES, CALIFORNIA.

GRINDING ART.

Application filed September 3, 1918. Serial No. 252,432.

To all whom it may concern:

Be it known that we, JOHN H. MACARTNEY and JACK MACARTNEY, both citizens of the United States, residing at Los Angeles, in 5 the county of Los Angeles and State of California, have invented and discovered new and useful Improvements in the Grinding Art, of which the following is a specification.

- 10 This invention and discovery relates to the art of comminution, trituration and levigation, and includes a method and means adapted to reduction of loose, broken materials to a required degree of fineness.
- 15 An object of this invention is to perform the required reduction, trituration or levigation with maximum ease and minimum expense, and in such a manner as to insure that the product of the triturating or levigating 20 process shall be practically free from particles of the apparatus by which the triturating or levigating operation is effected.

This invention and discovery relates to the formation and maintenance of triturating, 25 grinding or pulverizing surfaces, and also to the method whereby the reduction of the broken material is effected.

The discovery and invention is regarded as broadly new, primary and basic, in that 30 centrifugal and other forces are combined in a practical manner to produce out of broken material of the character to be reduced, an instrument by which the power required for the reductive work, is brought 35 into operation under conditions effective to such reduction; and also in that the mode of effecting the grinding operation is such as to attain the desired end of constantly renewing and making most effective the 40 grinding surfaces by which the reduction is to be accomplished.

We have discovered that it is possible to produce out of loose broken material a rigid body constituting a practical grinder capable of cooperating with another grinder or another body to reduce to any desired degree of fineness, material of the character of which the said broken material is composed, and that this may be accomplished by setting up centrifugal force through revolution 45 of broken material at a requisite speed to generate sufficient centrifugal force to hold the material outward subject to a restraining force operating continuously coaxial to the axis and normal to the plane 50 of rotation thereof to form an annular flat

faced mass so that by a resolution of forces the rigid grinder is so formed out of the material that is supplied to be ground; and that by relatively rotating two of such 60 grinders or by rotating one of such grinders relative to an opposing body adapted to cooperate therewith, the grinding action is effected in a practical manner.

Effective restraining force may inhere in 65 a peripheral wall to which the peripheral skin or surface of the revolving mass or body of broken material is held friction tight by centrifugal force, which also effects the building up of an annular body composed 70 of the broken material and having a revolving surface extending at right angles to the axis of revolution.

Where a plurality of such bodies are employed, a grinding operation may take place 75 between opposing surfaces of such bodies provided said bodies are non-synchronously rotated.

By so arranging the peripheral restraining means so as to space the non-synchronously revolving bodies a distance apart, a peripheral discharge will be produced consisting of comminuted material having a fineness determined by the separating space and also by the relative rotative speeds. 85

An object is to minimize the wear upon such mechanical means as may be employed to apply power to the work of reducing the broken material to the required fineness.

Other objects, advantages and features of 90 invention and discovery, may appear from the accompanying drawing, the subjoined detail description and appended claims.

The new method of pulverizing may be carried out in various ways; and various 95 means and different forms of apparatus may be employed to that end.

For the purpose of describing the same, reference is made to the accompanying drawings in which,

Figure 1 is an elevation in section on line α^1 Fig. 2, intended to illustrate the carrying on of the operations involved where two grinders are formed and caused to coact.

Fig. 2 is a view at right angles to Fig. 1, 105 as indicated by line α^2 in said Fig. 1. Parts are broken away to expose interior construction.

Fig. 3 is an enlarged detail fragment of Fig. 2, with finer material in the process of 110 grinding.

We have discovered that by a relative

regulated supplying of, and setting up centrifugal force within, the separate units *a* adapted to form an annular mass *b* of broken loose material of the character to be reduced to a greater fineness, and peripherally confining the mass in direct opposition to the operation of said centrifugal force upon such units so as to give a definite cylindrical form to the annular mass, we are able to produce a practically rigid and solid body having a flat continuous grinding surface *c* and also having a centrally located cavity *d*; and that by feeding broken material as at *e*, for further reduction, and for renewing and maintaining the grinding surface; a reduction is effected with sufficient speed and effectiveness; said flat face being brought into opposition to a corresponding face correspondingly formed for the purpose of effecting the grinding.

We have also discovered that upon opposing two of such flat grinding surfaces to each other, as at *c c'*, within two containers 1, 2, spaced apart a requisite slight distance, and supplying loose material of the same character to the cavity or chamber *d* formed within said containers at a distance internally, from the periphery of the mass, such supplied material will constantly renew both annular flat grinding surfaces thus constituted, as well as supply material to produce the requisite product; with maximized speed and minimized expenditure of power.

The size of the interior chamber into which the fresh broken material may be fed will enlarge or diminish according to the relative speeds of feeding and grinding. Increasing the feed, decreases the cavity, and vice versa if the speed of the grinders remain constant.

Our new method of grinding or crushing loose or broken material includes utilizing a regulated feed, centrifugal force and a force counter thereto to gather such material into, and hold such material in, a mass or masses flat faced and annular subjected to the rotative action by which the requisite centrifugal force is generated. This may be understood by reference to the drawings in which 1, 2, indicate hollow rotating heads containing masses *b*, *b'*, of broken material, the separate units *a*, of which are subject to the action of centrifugal force through the revolution of the masses *b*, *b'*, practically about a common locus 3, within the field or fields of revolution. The heads are shown as being revolved on axes 4, 5, that are eccentric to each other, so that the grinding faces will be relatively oscillated as well as relatively revolved. The regulated feed is indicated by the annular form of the masses.

The restraining or intercepting force which is opposed to the centrifugal force may be a component of any character effective to that end, and is indicated by the an-

nular rim walls 6, 7, by which it is understood the forms of the grinding surfaces will be determined. Each surface will vary in form and shape depending upon the speed of revolution of the mass or masses constituting such surface or surfaces, and said grinding surfaces at *c*, *c'*, of the two revolving bodies *b*, *b'*, of broken material will be extended approximately equidistant from a medial plane between the revolving bodies of material. The opposing faces 8, 9, of the rim walls 6, 7, are spaced apart according to the fineness of product desired.

The peripheral restraining means represented by the rim walls may be of any suitable character adapted to hold the material in opposition to the centrifugal forces set up in the two annular bodies respectively.

The two masses *b*, *b'*, are so placed that their grinding surfaces cooperate to grind the material supplied to the interposed cavity or chamber within them.

In the drawing, the masses are shown as revolving on or about a horizontal axis indicated at 3, and conveyor means comprising a tubular shaft 10, and a screw conveyor 11, which elements are means indicated for the purpose of supplying material from a hopper 12, to a central port 13, which is located at or about the medial plane of revolution so that the material that is fed into the chamber while said containers are being revolved in opposite directions, will take on motion immediately; whereby the broken material is put into a revolving state in two annular masses, the constituents of which are brought under control of centrifugal forces that operate at right angles to the axis of revolution, with the result that material being supplied to the interior of the chamber formed by the two containers forms the oppositely rotating annular contacting faces that become triturated and ground by the action of the rigid masses of material and the interposed loose units upon each other, and to form the central feed chamber.

The material being thus delivered at the medial plane or the meeting plane between the two grinding faces thus formed, at once serves to augment the grinding faces, and the innermost material will apply force to the pieces or separate units of material nearer the periphery to drive them directly outward; and also, by the resolution of forces, to drive such pieces or units from one side of the medial plane towards the mass on the other side of such medial plane, and vice versa; so that the centrifugal force not only acts to provide a practically solid and rigid grinding surface, but it also acts to cause the surfaces to deviate from a direction at right angles to the axis, so that at the medial plane near the periphery there is grinding not only of the surfaces formed

by the peripherally restrained, centrifugally impelled, pieces, but there is also caused a grinding action of piece upon piece at the medial plane.

5 The peripheral restraining means shown, are in the form of annuli, fixed by webs 14, 15, to the shafts 4, 5, by which they are revolved.

10 Said webs form end walls to restrain the material from displacement in directions parallel to the axis of revolution and are spaced apart from the plane of the opposite faces of the rim walls sufficiently to provide the cavity necessary to accommodate the 15 requisite grinding body or mass.

In the drawings the operation is indicated as being performed in such manner that the centrifugal lines of force act in vertical planes thereby causing that distribution of 20 the gravity fed material within the chamber or cavity inside the revolving bodies or masses, to occur without gravitational deflection from one to the other side of the meeting or medial plane where the pulverization is effected. Thus the chamber formed 25 within the mass contained within the adjacent containers, and the distribution of the material to the field where it is given the rotary motion by which centrifugal force is 30 generated and applied to bring the material into a rigid and practically solid form and to impose upon the mass the character of solidity, is made symmetrical and the operation is conducted with all the elements in 35 proper balance.

The discharge of the fine product thus also occurs in a vertical plane all around the rim walls and such product may be collected by a housing 16, and therefrom is gravitationally discharged through the bottom outlet 40 17, into any receiver, not shown.

By thus impelling under centrifugal force masses of broken material to be pulverized, and restraining such material at a 45 distance from the center of impulsion to form relatively revolving rigid bodies having opposed grinding surfaces within containers the opposed rim walls of which are spaced apart to allow discharge of fine material only between the outer rims of such 50 grinding surfaces and their containers, the grinding is effected without attrition upon the apparatus by the material to be ground; and by imposing upon the two bodies of 55 material, fields of revolution that are eccentric to each other, a criss-cross rubbing effect is secured so as to avoid scoring effects.

As the separate units are thus acted upon by centrifugal force they are caused to revolve or rotate more or less upon their individual center or centers of gravity, thus to facilitate disintegration and pulverization.

By revolving the masses of broken material about a horizontal axis and feeding

fresh broken material that is to be pulverized or reduced, centrally into said chamber, the material is caused to pass by force of gravity along the radii of the chamber until it contacts with the inner periphery of the 70 containers, the material will at once build up a lining inside the containers and such lining is constantly renewed, in a symmetrical manner by reason of the supplying of fresh loose units of the material centrally 75 between the opposed linings.

The outlet between the two rim walls may be adjusted as desired to change the fineness.

In Figs. 1 and 2 the units *a* to be crushed 80 are represented as consisting of broken rock of an average size as may be desired in reduction of ore, paint, clay or stone for any purpose requiring the material to be ground.

In Fig. 3 the units *a'* have been reduced 85 to a much greater fineness.

The product is indicated at 18 and may be in the nature of fine dust if the grinding is done dry or in the nature of suspensions if the grinding is done wet. 90

The speed of revolution must be such as to generate the requisite centrifugal force. Otherwise the work will not be effective.

A speed of from about 800 to 1200 revolutions more or less per minute is found to be 95 effective, and the speed of the feed will be made to correspond thereto, due consideration being given to the character of the material so as to form the annular grinding surfaces according to the principles here- 100 inbefore set forth.

We claim:—

1. The method of pulverizing material, which consists in impelling under centrifugal force masses of broken material to be 105 pulverized, and restraining such material at a distance from the center of impulsion to form relatively revolving circular rigid bodies having continuously opposed grinding surfaces, and allowing the discharge of 110 fine material only between the outer rims of such surfaces, and supplying fresh material to said grinding surfaces at the point of contact between such bodies.

2. In the art of pulverizing material the 115 method of forming a disc grinder which consists in impelling under centrifugal force masses of broken material to be pulverized, and restraining such material at a distance from the center of impulsion to 120 form a revolving circular rigid body having its grinding surface continuously in a plane perpendicular to its axis of rotation, and supplying fresh material at the axial center of the medial plane of said grinding surface.

3. The method of grinding or crushing loose or broken material by utilizing centrifugal force and a force normal thereto to gather such material into and to hold it 125

4
into annular mass and causing the material of one annular mass to continuously grind against the material of another similar mass, and supplying fresh material at the 5 axial center of the medial plane of said annular masses.

4. The method of forming broken or loose material into a grinder which consists in subjecting such material to the action of 10 centrifugal force within a revolving peripheral restrainer, and bringing a plurality of such grinders into contact with each other while revolving so as to form a continuous grinding surface, and supplying fresh material 15 at the axial center of the medial plane of said grinding surface.

5. The method of forming grinding apparatus out of loose or broken rock or other material by subjecting such material to the 20 action of centrifugal force and a force normal thereto, forming a plurality of rigid masses, and bringing a plurality of such masses into contact with each while each is revolving on its own axis; so that such rock 25 or other material will be ground or crushed by action of component units of one of such masses upon component units of another of such masses and thereby form a continuous grinding surface between said masses, and 30 supplying fresh material at the axial center of the medial plane of said rotating masses.

6. The method of grinding material substantially set forth which comprises subjecting two masses of said material to the action 35 of centrifugal force, restraining said material in such a manner that each of said masses forms a separate, continuous grinding surface, said two masses being so placed that their grinding surfaces cooperate to 40 grind the material therebetween and supplying fresh material to such masses at their grinding surfaces.

7. The method set forth of grinding material which consists in revolving two peripherally restrained masses of broken material 45 about a common axis, the axis of revolution of each mass being horizontal, and thereby generating sufficient centrifugal force to form said bodies respectively into 50 annular grinders; spacing the adjacent faces of the grinders apart to allow fine material to pass out at the rim; and causing fresh broken material to pass to the bodies at the medial plane between such bodies.

55 8. The method set forth of grinding loose or broken material which consists in holding such loose or broken material by means of centrifugal force within two opposite revolving containers in such a manner that 60 for all practical purposes a continual grind-

ing action takes place between the two masses of such material itself and not between such masses of material and their respective containers, and supplying fresh broken material to said masses at the axial 65 center of the medial plane of the rotating masses.

9. The method substantially set forth of holding loose or broken peripherally restrained material in place by centrifugal 70 force so that such loose or broken material may be continuously ground against a similar mass of said material held in like manner so that neither mass has any grinding 75 action upon its respective container and supplying fresh material to said masses at the axial center of the medial plane of the revolving masses.

10. The method set forth of grinding loose or broken material within opposed containers in which the material to be ground is held in place within such containers by centrifugal force in such manner that such material forms a protective lining for such containers and by the action of such centrifugal 80 force such material is gathered and formed into crushing or grinding masses having annular faces which continuously act upon each other to crush or grind such material and supplying fresh material to said masses 85 at the axial center of the medial plane of said grinding masses.

11. The method of pulverizing material, which consists in impelling under centrifugal force broken material to be pulverized, 90 restraining said material at a distance from the center of impulsion into annular masses to form said masses respectively into continuous annular grinders; supplying fresh broken material at the axial center of the 95 medial plane between said masses and allowing the discharge of the pulverized material only between the outer rims of the restraining means.

12. The method of grinding material, 100 which consists of forming by centrifugal force two oppositely revolving masses of the material to be ground, which serve as continuous grinders; supplying fresh material to said grinders at the axial center of the 110 medial plane of said masses, and allowing ground material only to peripherally pass out between said masses.

In witness whereof, we have hereunto set our hands at Los Angeles, California, this 115 10th day of August, 1918.

JOHN H. MACARTNEY.
JACK MACARTNEY.
